(57) **CLAIM**

The ornamental design for a universal travel adapter, as shown and described.

DESCRIPTION

FIG. 1 is a front elevational view of a universal travel adapter showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a front-top-left side perspective view thereof;

FIG. 8 is a rear-bottom-left side perspective view thereof;

FIG. 9 is a rear-bottom-left side perspective view of the universal travel adapter, shown in a first state of use;

FIG. 10 is a rear-bottom perspective view of the universal travel adapter, shown in a second state of use;

FIG. 11 is a rear-bottom perspective view of the universal travel adapter, shown in a third state of use; and,

FIG. 12 is a rear-bottom perspective view of the universal travel adapter, shown in a fourth state of use.

The broken lines in the drawings illustrate portions of the universal travel adapter which form no part of the claimed design.

1 Claim, 10 Drawing Sheets
